PROCESS OF MAKING ALCOHOL

Helmut G. Schneider, Westfield, and Vincent F. Mistretta, Fanwood, N. J., assignors, by mesne assignments, to Standard Oil Development Company, a corporation of Delaware

No Drawing. Application December 31, 1945,
Serial No. 638,590

10 Claims. (Cl. 260—639)

1

This invention relates to improvements in the manufacture of aliphatic alcohols, and more particularly to the manufacture of aliphatic alcohols from olefinic hydrocarbons.

In the production of aliphatic alcohols as, for example, secondary alcohols from hydrocarbon naphthas or gases, the naphtha is contacted with an acid, usually sulfuric acid, to form an acid extract. The strength of the acid employed depends upon the olefin to be extracted. For the absorption of propylene it is customary to use 90—95% H_2SO_4 , and for normal butenes, acids of 80—90% on a hydrocarbon-free basis are employed. After the acid extracts are formed, they are diluted with water or other aqueous materials to an acid concentration of 30—60% on a hydrocarbon-free basis, hydrolyzed and stripped to recover the alcohol. During the recovery of alcohols from these acid extracts there is always appreciable decomposition of the extract to olefins which lowers the alcohol recovery yield. The regeneration of olefin is particularly noticeable in the manufacture of butyl alcohol. In order to conserve the regenerated olefin, it has been suggested that the olefin be cooled and recycled to the extract as it leaves the absorber or at some point between the absorber and the hydrolyzer. The difficulty with this suggestion is that the strong acid extracts contain considerable amounts of entrained or physically dissolved saturated hydrocarbons. The result is that when such extracts are stripped, the regenerated olefin from the stripping stills is contaminated with a large amount of saturated hydrocarbons. Where the gases containing regenerated olefins and saturated hydrocarbons are recycled to extract, which also contains saturated hydrocarbons, as has been suggested, the saturated hydrocarbons quickly build up in the recycle system to the point where the recycle gases are largely saturated hydrocarbon, and the olefin absorption efficiency of the recycle system is thereby lowered. It therefore becomes necessary to vent the saturated hydrocarbon at some point in the recycle system in order to prevent the build-up described. Although requisite in such a system, the venting of saturated hydrocarbons entails a certain loss in olefins.

The present invention has for its principal object keeping at a minimum the amount of saturated hydrocarbons present in the hydrocarbon gases produced in the alcohol stripping step of a process wherein aliphatic olefins are converted to aliphatic alcohols. A further object is to accomplish the substantial elimination of saturated hydrocarbons from the effluent gases of an alcohol stripping still without incurring any con-

2

siderable loss of potential alcohol in the form of regenerated olefins. These and other objects are achieved by the practice of the invention disclosed in the following description.

5 It has now been found that through the employment of carefully controlled operating conditions both entrained and physically dissolved saturated hydrocarbons can be removed from saturated acid extract without excessive loss of 10 potential alcohol due to regenerated olefin. According to the present invention the strong acid extract from an extraction system or absorber is diluted with water, cooled and de-gassed to remove substantially all the saturated hydrocarbons from the extract.

Although water is mentioned as the diluent, diluted aqueous solutions of acid may be used if desired in which case the acid would be the same as that used to absorb the olefin in the first instance. In practice the strong acid extract is diluted to an acid concentration of 40—75% on a hydrocarbon-free basis and the degassing is conducted at atmospheric pressure or substantially atmospheric pressure. Dilution of the saturated 25 acid extract and reduction in pressure may be carried out simultaneously, although it is preferred, for reasons of olefin conservation, to dilute the saturated extract to the desired acid concentration and then cool to a temperature of 30 30—40° C. The step of liberating the saturated hydrocarbons from diluted acid extract requires from 5—15 minutes, depending upon the acid concentration of the diluted extract and the temperature employed. After removal of the saturated hydrocarbon, the diluted extract may then be hydrolyzed and stripped to recover alcohol in the usual manner. Some olefin in substantially pure form will be regenerated during hydrolysis and stripping. This olefin can be recycled to 40 the saturated extract from the absorber without adding appreciably to the amount of saturated hydrocarbons present in the saturated extract. The effluent gases liberated from the diluted extract when the pressure is released will consist 45 predominantly of saturated hydrocarbons and a small amount of regenerated olefin. Such gases may be recycled to the absorber to recover the olefins contained therein.

It is preferred to carry out the degassing of acid 50 extracts at low acid strength, i. e. 40—75%, on a hydrocarbon-free basis for the reason:

(1) That the absorption of olefin by acid is normally conducted at superatmospheric pressures. This results in increased solubility of saturated 55 hydrocarbons in the extract. When the pressure on such an extract is subsequently relieved considerable foaming occurs which in commercial op-

eration is difficult to control. If, however, the saturated extract is diluted with water before or during the pressure releasing step, the foaming is almost entirely eliminated, and

(2) degassing acid extracts either after or during dilution results in a more complete removal of the saturated hydrocarbon contained therein.

It has been found that, when the pressure on a saturated extract, which may also be designated as a strong extract in the sense that the acid on a hydrocarbon-free basis is still of the same concentration used in absorbing olefin, is reduced, only about half the saturated hydrocarbons are removed. This is due to the fact that even at atmospheric pressure saturated hydrocarbons are appreciably soluble in strong acid extracts. On the other hand, when the extract is diluted prior to the release of pressure it is possible to get substantially complete removal of the saturated hydrocarbons.

It is important in carrying out the degassing of dilute extracts that the operating conditions be carefully controlled, to avoid decomposition of the extract to olefin. Any olefin regenerated during the degassing step represents the loss of potential alcohol in the extract. Close control of the acid strength in the extract and temperature to which saturated hydrocarbons are liberated needs close supervision to maintain olefin regeneration at a minimum. When a strong acid extract is diluted the reaction is exothermic and there is sufficient heat liberated to raise the temperature of the mixture to 50-60° C. from an extract temperature of 30-35° C. At temperatures of 50-60° C. the rate of decomposition of the extract to olefin is quite rapid, and the contact time in the degassing drum should be much shorter than would be required at lower temperatures. However, even with the shorter contact time at high temperatures there is much larger decomposition than at 30-40° C. Accordingly, the acid extract is cooled during dilution in order to maintain the temperature between the limits of 30-40° C., or after diluting the extract to the desired acid concentration it is immediately cooled to 30-40° C. following the dilution stage and prior to the degassing operation in order to reduce the decomposition of the extract to olefin to a minimum.

The following examples will serve to illustrate the invention:

Example 1

For the purpose of demonstrating the solubility of saturated hydrocarbons in extract, a butyl extract of 1.179 molar saturation (mols C₄H₈/mol H₂SO₄) and 88% acid strength was agitated with C₄ naphtha at 20° C. and 20 lbs. gauge pressure for 60 minutes, and then permitted to settle for 120 minutes. A sample of this extract was then diluted with water, maintaining the temperature during dilution at less than 40° C. to 10% acid strength. 10% acid strength was chosen because at this strength or lower, dilute acid and acid extracts do not dissolve hydrocarbons. The pressure was then released and the gas given off measured. The volume of gas recovered was equivalent to 2.33 cubic feet per gallon of extract.

Example 2

The following experiment shows that by releasing pressure on a butyl extract (88% acid strength) it is possible to remove only about half the entrained saturated hydrocarbons in the extract. Without water dilution it would be difficult to remove the remaining saturated hydrocarbon dissolved at atmospheric pressure.

Molar Saturation of Butyl Extracts (88 Per Cent. Acid)	Total Saturant per Gallon of Extract at 20# Pressure and 20° C.	Volume of Saturated Hydrocarbon Liberated On Reducing Pressure to Atmospheric	Per Cent Saturated Hydrocarbons Removed by Reducing Pressure
1.18	Cubic feet 2.374	Cubic feet 1.204	51
1.17	2.218	0.598	43

Example 3

Samples of the extract made as described in Example 1 were then diluted with water, maintaining the temperature at 40° C. to give acid strength of 42.6%, 51.5%, 61.7% and 75.7%. The gas given off on degassing these dilute extracts at a temperature of 40° C. and atmospheric pressure was measured and analyzed with the following results:

Acid Strength of Extract	Contact Time in Degassing Drum	Saturate Removal
Per cent	Minutes	Per cent
42.6	5	84.3
42.6	15	95.6
51.5	5	91.5
51.5	15	98.0
61.7	5	88.4
61.7	10	96.4
61.7	15	98.3
75.7	5	92.5
75.7	10	97.3
75.7	15	100

It will be noted from the above that with these dilute extracts degassing is practically complete and contact time between 10 and 15 minutes is sufficient to remove the saturated hydrocarbons.

Example 4

It has been found that acid extracts decompose to some extent under all degassing conditions. However, this decomposition can be held to a minimum by controlling the degassing temperature at 40° C. or less. The effects of acid strength and temperature on olefin regeneration from acid extracts during the liberation of saturated hydrocarbons is illustrated in the table shown below.

Samples of extracts prepared as described in Example 1 were diluted to approximately 40, 50, 60 and 75% H₂SO₄ and degassed at 40°, 50°, 60° and 70° C. under atmospheric pressure. The gases liberated during degassing were collected, measured and analyzed for saturated hydrocarbons and olefin with the following results:

Acid Strength	Degassing Temp.	Contact Time	Saturates Removed	Extract Decomposed to Olefin
Per Cent.	°C.	Min.	Per Cent.	Per Cent.
42.6	40	5	84.3	0.24
40.2	50	5	95.6	0.56
40.7	60	5	100	1.23
		15		1.48
38.5	70	5	100	1.39
51.5	40	5	91.5	3.17
		15		0.43
50.7	50	5	98.0	0.62
61.7	40	5	100	0.79
		10		0.61
		15		0.85
59.7	50	5	98.3	0.97
75.7	40	5	100	1.3
		10		0.82
		15		1.07
75.5	50	5	97.3	1.35
		10		1.41
		15		3.16
75	50	5	100	4.8
		10		1.92
		15		2.71
				4.4

The results of these experiments show that as the acid strength and temperature increase, decomposition of extract to olefin also increases. The acid strength used for degassing will be dictated largely by the conditions required for subsequent hydrolysis and stripping to recover alcohol. The result is that the decomposition on degassing will have to be controlled largely by the temperature and contact time. From the above results it can be seen that the temperature should be as low as possible, preferably between 30-40° C. and the contact time sufficiently long, 10-15 minutes to permit the saturant to escape. Lower temperatures require that the extract be cooled subsequent to dilution. If this is not done the only other alternative, as shown by the foregoing results, is to have a very short contact time and provide plenty of surface such as a packed tower for the removal of saturated hydrocarbons. However, the latter will give somewhat higher olefin regeneration for a given saturated hydrocarbon removal.

What is claimed is:

1. A process for removing saturated hydrocarbons from an acid extract which comprises contacting a hydrocarbon stream containing mono-olefins and saturated hydrocarbons with a strong mineral acid absorbent at a temperature of 15° C. to 100° C. and at a pressure of 15 to 500 p. s. i. g. to form an acid extract, maintaining the acid extract at a pressure of 15 to 500 p. s. i. g. while diluting the acid extract with an aqueous diluent to an acid strength of 40 to 75 wt. % on a hydrocarbon free basis, cooling the extract to a temperature below 40° C., thereafter reducing the pressure on the cooled extract to atmospheric pressure to release saturated hydrocarbons therefrom and separating the released saturated hydrocarbons from the acid extract.

2. A process for removing saturated hydrocarbons from a sulfuric acid extract which comprises contacting a hydrocarbon stream containing mono-olefins and saturated hydrocarbons with sulfuric acid of 70 to 98 wt. % concentration at a temperature of 15° C. to 100° C. and at a pressure of 15 to 500 p. s. i. g. to form a sulfuric acid extract, maintaining the sulfuric acid extract at a pressure of 15 to 500 p. s. i. g. while diluting the acid extract with water to an acid strength of 40 to 70 wt. % on a hydrocarbon free basis, cooling the extract to a temperature below 40° C., thereafter reducing the pressure on the cooled acid extract to atmospheric pressure to release saturated hydrocarbons therefrom and separating the released saturated hydrocarbons from the acid extract.

3. A process for producing an aliphatic monohydric alcohol which comprises contacting a hydrocarbon stream containing mono-olefins and saturated hydrocarbons with a strong mineral acid at a temperature of 15° C. to 100° C. and at a pressure of 15 to 500 p. s. i. g. to form an acid extract, maintaining the extract under pressure of 15 to 500 p. s. i. g. while diluting the extract with an aqueous diluent to an acid strength of 40 to 75 wt. % on a hydrocarbon free basis, cooling the extract to a temperature below 40° C., thereafter reducing the pressure on the cooled ex-

tract to atmospheric pressure to release saturated hydrocarbons therefrom, hydrolyzing the degassed extract and recovering aliphatic monohydric alcohol from the hydrolyzed extract.

5. A process according to claim 3 in which the strong mineral acid is 70 to 98 wt. % sulfuric acid on a hydrocarbon free basis, and in which the aqueous diluent is water.

5. A process for producing secondary butyl alcohol which comprises contacting a hydrocarbon stream containing normal butenes and saturated hydrocarbons with sulfuric acid of 80 to 93 wt. % on a hydrocarbon free basis at a temperature of 15 to 75° C. and at a pressure of 15 to 100 p. s. i. g. to form an acid extract, maintaining the acid extract under pressure of 15 to 100 p. s. i. g. while diluting the extract with water to an acid strength of 40 to 75 wt. % on a hydrocarbon free basis, cooling the extract to a temperature below 40° C., thereafter reducing the pressure on the cooled extract to atmospheric pressure to release saturated hydrocarbons therefrom, hydrolyzing the degassed extract and recovering secondary butyl alcohol from the hydrolyzed extract.

6. A process according to claim 5 in which the dilution and cooling operations are carried out simultaneously.

7. A process according to claim 5 in which the cooled extract is held at atmospheric pressure for about 10 to 20 minutes.

8. A process for producing isopropyl alcohol which comprises contacting a hydrocarbon stream containing propylene and saturated hydrocarbon with sulfuric acid of 65 to 93 wt. % concentration at a temperature of 15° C. to 100° C. and at a pressure of 75 to 500 p. s. i. g. to form an acid extract, maintaining the extract under pressure of 75 to 500 p. s. i. g. while diluting the extract with water to an acid strength of 40 to 75 wt. % on a hydrocarbon free basis, cooling the extract to a temperature below 40° C., thereafter reducing the pressure on the cooled extract under atmospheric pressure to release saturated hydrocarbons therefrom, hydrolyzing the degassed extract and recovering isopropyl alcohol from the hydrolyzed extract.

9. A process according to claim 8 in which the acid extract is diluted and cooled simultaneously.

10. A process according to claim 8 in which the acid extract is held at atmospheric pressure for about 10 to 20 minutes.
